UNITED STATES PATENT OFFICE.

FREDERICK A. PRESTON, OF HIGHLAND PARK, ILLINOIS, ASSIGNOR TO THE P & M COMPANY, OF CHICAGO, ILLINOIS. A CORPORATION OF ILLINOIS.

BOND-WIRE SUPPORTER.

Application filed December 30, 1922. Serial No. 609,806.

My invention relates to bond wire supporters, that is to say, to devices for supporting, intermediate their ends, the wires used for bonding or making electrical connections between abutting rails of a railroad track; and the object of the invention is to provide a new and improved bond wire supporter which can be cheaply manufactured and easily applied to the rail and which will hold the bond wire or wires in proper position against the angle bar or splice bar employed for making the joint between the rails in such manner that the wire or wires cannot be removed from the supporter without removing or at least loosening the nut of the track bolt which fastens the supporter to the splice bar.

It is a matter of considerable importance, and one concerning the safety of the traveling public and those operating railroad trains, that the wires used for bonding the rails, particularly the bonding wires used on steam railroads for insuring the transmission through the track of signaling currents, should be held in their proper place against displacement accidentally or through malice or ignorance, since the proper functioning of the signaling mechanism depends upon maintenance of a continuous current through the track.

Bond wires are usually of such length that when attached to adjacent rails there is enough slack to allow the wires to be bent over on the ball of the rail in a position to be cut by the wheels of passing trains or to be bent down on the ballast or away from the rail, in which positions they are likely to be injured through the ignorance of the track men or torn from the rails by dragging rigging on the trains. The same considerations which make it desirable to fasten or clip bond wires at points intermediate their ends to the splice bars, should require also that these attachments be reliable and capable of withstanding some force and that they should be such that cannot be easily tampered with either ignorantly or maliciously. Unless the wires are so fastened to the splice bar there is a chance of their being disengaged from the supporter or clip by the dragging rigging on passing trains. It also happens sometimes that bond wires are deliberately and maliciously pulled away from their clips and over the ball of the rail by trespassers in order that they may be

cut and destroyed. Not infrequently trackmen, not maliciously but through ignorance, finding the wires in the way, will either bend them upwardly or downwardly out of their proper place in order to more conveniently reach some part of the track on which he is working. My invention has these several contingencies in view and seeks to provide a supporter which, besides being inexpensive to manufacture, will serve to hold the wire or wires in their proper place positively and so long as the track bolt nut is not removed or loosened instead of merely clipping them to or retaining them against the splice bars as has been customary. Even a maliciously inclined person is not likely to go so far as to loosen a track bolt since such act is likely to be detected and if detected will be severely punished. The invention has in view in its more specific aspect, a bond wire supporter for use in connection with a splice bar having an outwardly projecting shoulder along its upper edge as shown in the annexed drawing.

In the drawing, which illustrates a preferred embodiment of my invention,

Fig. 1 is a cross sectional view of a railroad rail and its splice bar with the bond wire supporter of my invention attached thereto.

Fig. 2 is a view, in perspective, of the supporting device shown in Fig. 1, and

Fig. 3 is a view, in elevation, of the inside of a slightly modified form of the invention.

Referring to the drawing, 10 designates a railroad rail and 11, 11' the splice or angle bars for making the joint between abutting rails, the term "abutting" being used with only approximate correctness because according to the usual practice spaces for expansion exist between the adjacent ends of the rails of a railroad track. 12 indicates one of the track bolts for securing the splice bars 11, 11' to the rail 10, and 13 a nut for bolt 12.

Referring first to the form of the invention shown in Figs. 1 and 2, the supporter consists of a strip of metal 14, preferably of steel having some resiliency, the lower end 15 of which (having reference to the more usual position of the device on the track) is formed with an opening 16 for the track bolt 12. Above this apertured part the strip is formed with an outwardly projecting offset 17 and the remaining portion of the strip

is bent to form a loop 18 for the bond wires, two of which are shown in Fig. 3 and designated 19, the extremity of the strip providing a tongue 20 which, as the device is manufactured, stands close to but out of contact with the portion 21 of the strip on the other side of loop 18 so as to leave a space or channel 22 for insertion of the bond wires into the loop. Preferably the tongue 21 is formed with an inwardly projecting lip 23 which has substantially the inclination of offset 17.

In attaching the supporter to the rail joint nut 13 is removed from bolt 12, the supporter is slipped over the bond wires 19, which pass into the loop 18 through the open channel 22, and the nut 13 is then replaced on the bolt and screwed down so as to clamp the supporter against the outwardly projecting shoulder 24 on the upper edge of the splice bar 11, thus closing the loop by bringing tongue 20 against the opposite portion 21 of the device and the lip 23, which extends under the shoulder 24 of the splice bar, against the offset portion 17 of the supporter.

With the bond wires held in this manner at one or more points intermediate their ends (the usual practice being to use two supporters for each joint), it is impossible to detach the wires from the supporter without removing the nut 13. Moreover, the wires are held with practical certainty against accidental detachment since it is hardly possible to exert sufficient force on the wires to pull the tongue 20 away from its binding engagement with the splice bar. The device is preferably made of spring steel yielding enough so that the loop is closed, or to all intents and purposes closed, when the device is attached to the splice bar but stiff enough so that the upper part of the device cannot be bent, without exerting considerable force, to open up the loop.

In Fig. 3 I have shown a modified form of bond wire supporter, designated 25, which has the general configuration of the device shown in Figs. 1 and 2, but omits the lip 23 and is provided with an open recess 26 at its lower end so that it may be slipped off and on the track bolt by merely loosening the nut 13.

While I have assumed that the bond wire supporter of my invention would be used on the nut end of the bolt it is obvious that it might be used at the other end of the bolt although less conveniently.

I claim:

1. A bond wire supporter for attachment by a fastening device to a railroad rail splice bar having an outwardly projecting shoulder at its upper edge consisting of a metal strip, the lower end of which is formed for engagement with said fastening device and the upper end of which is offset outwardly from the lower end, is bent over to form a loop for the bond wire and a tongue which intervenes between the shoulder of the splice bar and the part of the supporter on the opposite side of said loop to close said loop when the supporter is secured to the splice bar.

2. A bond wire supporter for attachment by a fastening device to a railroad rail splice bar having an outwardly projecting shoulder at its upper edge, consisting of a metal strip formed at its lower end for engagement with said fastening device and at its upper end with a portion offset outwardly from the lower end and bent over to form a loop for the bond wire, and a tongue which intervenes between the shoulder of the splice bar and the part of the supporter on the opposite side of said loop to close said loop when the supporter is secured to the splice bar, said tongue being provided with an inwardly projecting lip which extends under the splice bar shoulder.

FREDERICK A. PRESTON.
